DESIGN FOR A LADY'S COAT

Louis A. Siegel, Mount Vernon, N. Y.

Application October 27, 1936, Serial No. 65,529

Term of patent 3½ years

To all whom it may concern:

Be it known that I, Louis A. Siegel, a citizen of the United States, residing at Mount Vernon, in the county of Westchester and State of New York, have invented a new, original, and ornamental Design for a Lady's Coat, of which the following is a specification, reference being had to the accompanying drawing, forming part thereof, wherein,

The characteristic features of my design reside in the wide curved lapels of the configuration shown in combination with the four buttons and four pockets arranged on the princess coat as shown.

I claim:

The ornamental design for a lady's coat substantially as shown and described.

LOUIS A. SIEGEL.
